UNITED STATES PATENT OFFICE

EMIL GATHMANN, OF BALTIMORE, MARYLAND

SHRINK-HEAD CASING FOR INGOT MOLDS

Application filed July 14, 1928. Serial No. 292,703.

This invention relates broadly to the art of casting steel ingots in metallic molds equipped with shrink head or feeder casings made of refractory and of heat-insulating material, and more particularly to an improvement in the type of construction of said shrink head casings.

In several U. S. Letters Patents heretofore granted to me, No. 1,643,241 for instance, I have shown molds for casting steel ingots in which provision is made for conserving the heat of the molten metal at the top of the ingot and for cooling said ingot or casting from the bottom upwardly. A mold of the type described in the aforementioned Letters Patent, when used in connection with the improved type of shrink head casing described in the present application, will produce a physically sound ingot body with a greatly lessened percentage of shrink head volume, as I am thereby enabled to maintain the molten steel forming the uppermost or shrink head portion of the ingot in a fluid condition until the metal composing the body of the ingot 25 has cooled and solidified progressively from the lower portion to the top.

United States Letters Patents have heretofore also been granted to me for improvements in shrink head casings and I refer specifically to Patents No. 1,258,209 of March 5, 1918, and No. 1,508,931 of September 16, 1924, and No. 1,696,395 of December 25, 1928. While the shrink head casings heretofore known in the art have been satisfactory either as refractories or as conservers of heat, they have not had these qualities combined in an inexpensive unit structure suitable for use in commercial ingot production.

Because of the inefficient heat-insulating qualities of the shrink head casings heretofore used, the common practice, since the grant of my Patent No. 1,049,573 of January 7, 1913, has been to employ shrink head casings having a chamber volume equal to approximately 15% of the total ingot, altho the actual shrinkage of well-deoxidized, high carbon steel from the liquid to the solid state has been ascertained to average but 3% of the ingot volume when the metal is teemed at suitable temperature. Therefore, a rel-

atively high percentage of steel is wasted in the shrink head in order to insure of soundness in the ingot body.

Means have been proposed for pre-heating the walls of the shrink head casing and the upper part of the ingot mold chamber in order to lessen the required volume of the shrink head chamber, but the apparatus required is too cumbersome and expensive for tonnage production and has been used to a very limited extent.

The primary object of my invention is to provide a shrink head casing of unit structure, the exterior walls of which are relatively strong and highly refractory and the interior or core portion of which is formed of a cellular material, the air cells of which prevent the conduction and the radiation of the heat of the molten metal contained within the shrink head.

My improved shrink head or feeder comprises an outer casing of highly refractory fire clay which has a sintering point preferably above the pouring temperature of liquid steel, and an inner core portion of porous material such as infusorial earth or diatomite, which, though less refractory than the material forming the outer casing, is a much better insulator and heat conserver than said casing material. I thus obtain a mold top or feeder having the heat-insulating qualities essential to efficient shrink head construction without sacrificing the important factor of strength of a high refractory structure.

In the accompanying drawings:

Figure 1 shows a longitudinal section of a shrink head casing constructed in accordance with my invention.

Figure 2 is a cross sectional view on line 2-2 of Figure 1, and

Figure 3 is a vertical central section of an ingot mold fitted with a shrink head casing of the type shown in Figure 1, a solidified ingot being contained therein.

Referring to Figures 1 and 2 of the drawings, the shrink head casing 5 consists of an inner or core portion 7 formed of a material having a high heat insulating value, this material being of a very open or cellular structure, such as infusorial earth, diatomite or

the like. Surrounding the core portion 7 is a casing 8, having inner walls 9 and outer walls 10, the casing 8 being formed of highly refractory material, the preferred material being fire clay having a sintering point approximately equal to or in excess of the temperature of liquid steel.

Figure 3 illustrates a Gathmann big-end-up type of mold 1 fitted with a feeder or mold top 5 of the type shown in Figures 1 and 2. 10 A solidified ingot 2 is graphically illustrated therein. The mold has side and bottom walls 3 and 3' and is supported by a stool or plate 4. A quantity of heat-conserving material 6 shown on the top of the ingot within the shrink head casing prevents the radiation of heat from the top of the ingot, thereby aiding in the progressive solidification of the metal from the bottom upwardly.

20 In manufacturing my improved shrink head casing, I preferably first form or mold the inner or core portion 7 into the desired shape and suitably dry or bake it. I then form or mold around the core portion the casing 8 of highly refractory fire clay. I 25 make the walls of the casing 8 relatively thin as compared to the total thickness of a wall of the completed shrink head casing; but since the core portion 7 has little mechanical 30 strength, I preferably make the walls of the casing 8 of sufficient thickness to give the shrink head casing as a whole the necessary 35 rigidity and structural strength to withstand handling and shipping without undue breakage.

After the outer casing 8 has been formed so as to surround the core portion 7, the complete shrink head casing is placed in a kiln for burning or baking and thus hardening the fire clay casing 8. During the kiln drying or burning operation the outer casing becomes denser as it hardens, while the inner or core portion 7 becomes even more porous than it was when first formed.

45 I preferably make the height of my improved shrink head casing somewhat greater than the average inside diameter of the shrink head casing chamber 11. As a result of so apportioning the dimensions of my shrink head casing and due to the superior heat 50 conserving qualities of the core portion of said casing I am enabled to make the volume of the chamber of the shrink head casing equal to approximately only 8% to 10% of 55 the total volume of the ingot in the molding of which the casing is used.

As stated in my U. S. Patent No. 1,711,052 of April 30, 1929, when using my improved shrink head casing, and a metallic mold, I am 60 enabled to reduce the percentage of the solidified metal in the shrink head to as little as 5% of the volume of the entire solidified ingot.

It is then apparent that by thus construct- 65 ing a shrink head casing, the core portion of

which is very porous and the outer walls or the matrix of which are highly refractory and relatively strong, I am enabled to greatly reduce the volume of the chamber of the shrink head casing, thereby effecting a very considerable saving of the steel which must be cropped from the ingot, whereas, when using other types of hot tops or feeders it is necessary to crop a considerably greater amount of steel from the ingot. In reducing the percent of the total ingot metal which must be cropped I obtain a greater yield of sound, workable ingot metal from the total metal poured into the mold.

I claim as my invention:

1. A shrink head casing for ingot molds 80 comprising a core of highly heat-insulating but structurally weak material and inclosing refractory walls that are of a stronger structure and which are self-supporting.

2. A self-supporting shrink head casing for ingot molds comprising a structurally weak core of high heat-insulating cellular material supported by inclosing walls of refractory material as and for the purpose 90 specified.

3. A shrink head casing for ingot molds comprising a porous core of highly heat-insulating material and outer walls which are highly refractory and relatively strong and 95 self-supporting.

4. A shrink head casing for ingot molds comprising outer walls of strong self-supporting fire clay and a core of cellular material which is relatively weak and which possesses relatively high heat-insulating properties as compared with the outer walls which inclose it.

5. A shrink head casing for ingot molds comprising outer walls of fire clay and non-combustible core of cellular material which is relatively weak, but which possesses relatively high heat-insulating properties as compared to the outer walls which inclose it.

In testimony whereof, I have hereunto subscribed my name.

EMIL GATHMANN.
